(57) CLAIM

The ornamental design for a furniture set, as shown and described.

DESCRIPTION

FIG. 1 is a perspective view of a furniture set, showing my new design;

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof;

FIG. 8 is a perspective view showing the chair component of the furniture set of FIG. 1, shown separately for completeness of illustration;

FIG. 9 is a perspective view showing the 2-seater sofa component of the furniture set of FIG. 1, shown separately for completeness of illustration;

FIG. 10 is a perspective view showing the 3-seater sofa component of the furniture set of FIG. 1, shown separately for completeness of illustration; and,

FIG. 11 is another perspective view of FIG. 1 in different configuration of use.

All the broken lines in the drawings depict portions of the furniture set that form no part of the claimed design.

1 Claim, 11 Drawing Sheets
